R. M. MORGAN

By *J. P. Wacham, Jr.*

UNITED STATES PATENT OFFICE.

GEORGE JAMES MORGAN AND RICHARD MILLWARD MORGAN, OF CEFN COED, NEAR MERTHYR TYDVIL, WALES.

DEVICE FOR THE REMOVAL OF INTERNAL-COMBUSTION ENGINE VALVES.

Application filed December 12, 1922, Serial No. 606,537. Renewed March 10, 1925.

To all whom it may concern:

Be it known that we, GEORGE JAMES MORGAN and RICHARD MILLWARD MORGAN, subjects of the King of Great Britain and 5 Ireland, and residents of Cefn Coed, near Merthyr Tydvil, county of Glamorgan, Wales, have invented a certain new and useful Improvement in Devices for the Removal of Internal-Combustion Engine Valves, of 10 which the following is a specification.

This invention relates to a simple and certain means for the compressing of valve springs of motor car and other internal combustion engines, enabling the keys or 15 cotters of said valves to be quickly and safely removed, without fear of damage to fingers. Further, the device enables the cotters of two valves to be removed, if necessary, with one setting.

20 Broadly speaking, our invention comprises a pair of plates constructed and adapted to be inserted in superimposed fashion between the valve spring cups or equivalents and the tappet heads, and adapted 25 to be prized apart so that one bears against the tappet head and the other against the valve spring cups or equivalents, causing the latter to be moved up the valve stems.

30 The apparatus in accordance with our invention more particularly comprises two co-acting plates of steel or other suitable metal, each formed with apertures, opening out 35 of the side of the plate, said plates being adapted to be placed in superimposed fashion between the appropriate valve spring cups and tappets heads. That is to say, one plate, (hereinafter termed the "lifting plate") is adapted to slide laterally on to 40 the ends of the valve stems below the usual spring-retaining cups, so that said valve stems are received within its respective apertures, and the other plate (hereinafter referred to as the "locking plate") is 45 adapted to slide laterally to a position by the side of said lifting plate, on the tappet side thereof. In action, separation of the two plates from one another causes the outer face of the lifting plate to contact 50 with the valve spring cups, and the outer face of the locking plate to press on to the tappet heads, and since said tappets offer resistance, the valve springs are caused to be compressed by the raising of their re-

taining cups by the lifting plate. The cotters may then be removed between the two plates.

Further features of our invention will become apparent from the accompanying drawings, in aid of the following description. In the drawings:

Figure 1 is a plan view of a lifting plate; and,

Figure 2 a longitudinal section through *a*—*b* in Figure 1.

Figure 3 is a plan view of a locking plate; and,

Figure 4 a longitudinal section through *c*—*d* in Figure 3.

Figures 5 and 6 are similar views to Figures 1 and 2 of a modified form of lifting plate; and,

Figures 7 and 8 similar views to Figures 3 and 4 of a modified form of locking plate.

Figure 9 is a diagrammatic view showing the application of the device.

Similar parts in the several views are indicated by like letters of reference.

The apparatus comprising a lifting plate *a* formed at each end with an aperture *a*¹, 80 conveniently of circular shape, each of the two apertures *a*¹ opening into the same side of the plate by the formation of a neck *a*². A locking plate *b* is formed with an aperture *b*¹ at each end, both of said apertures *b*¹ 85 opening out to the same side of the said plate.

The two plates are adapted to slide laterally on to the ends of the valve stems between the valve spring cups and tappet heads as seen more clearly in reference to Figure 9, the apertures *a*¹ and *b*¹ of the plates *a* and *b* respectively, receiving said valve stems which enter via the openings in the sides of the plates.

The outer surface *c* of the lifting plate around its aperture *a*¹ is adapted to contact with the valve spring cup (see Figure 9) and the outer surface *d* of the plate *b* about its aperture *b*¹ is adapted to contact with the tappet head, the inner edges *e* of the two plates when in position contacting with one another.

It will be followed that separation of the two plates away from one another will cause the surface *d* of the plate *b* to press down on to the tappet heads, and since said tappet heads offer resistance, the surface *c*

of the plate *a*, pressing against the valve spring cups, will cause said cups to move up the valve stems and compress the springs.

To facilitate separation of the two plates 5 a shallow slot *f* is formed in either one or both of the two meeting surfaces, and in the case where both are slotted the slot of the bottom plate is serrated, and the two slots together when the plates are in position as seen in Figure 9, form a rectangular 10 passage. Said passage serves for the reception of a flat key, screwdriver blade or the like, which, given a half-turn, serves to bring it from its flat, to edge position, causes 15 separation of the two plates.

In order to prevent the plates slipping when in use, the upper surface *c* of the plate *a* is formed with an annular recess *g* about the aperture *a*¹, for the reception therein of 20 the valve spring cup. In the construction of lifting plate shown in Figures 1, 2 and 9, said recess is of square formation, whilst in the construction shown in Figures 5 and 6, said recess is of saucer shape. The locking plate *b* shown in Figures 3, 4 and 9 is formed on its lower surface *d* about the 25 apertures *b*¹ with annular recesses *h* adapted to receive the tappet heads, whilst the construction shown in Figures 7 and 8 has no 30 such recess.

A slot or gap *i* may be formed in the lower surface of the plate *a*, if necessary, opposite the opening *a*² of the aperture *a*¹, and when the said plate is raised to compress the 35 spring, said gap *i* allows a passage for the extraction of the cotter pins. Said gap need not necessarily extend completely through from the aperture *a*¹ to the exterior.

The shape of the recesses *g* and *h*, and of 40 the apertures *a*¹ and *b*¹, and the thickness of the plates, as well as the dimensions of the device, depends on the particular make of engine to which the device is intended to apply.

45 The plates are preferably reduced in

width about their centre of length to form a waist as shown.

It will be followed that the width of the tool which may be inserted in the aperture formed by the slots *f*, depends on the width 50 of said aperture, and the distance that the two plates may be separated from one another is consequently governed thereby. As the said aperture is at the centre of length of the plates, equal lifting pressure obtains 55 at both ends of the lifting plate.

We claim:—

1. A valve spring compressing device consisting of a pair of complementary separate plates adapted for superimposed insertion beneath the valve spring cups, said plates being so constructed that they may be pried apart by a separate tool or implement. 60

2. A valve spring compressing device consisting of a pair of complementary separate plates adapted for superimposed insertion beneath the valve spring cups, said plates having matching groove portions which provide an opening for receiving a separate tool or instrument whereby they may be pried 70 apart. 65

3. A valve spring compressing device comprising a pair of normally separate but cooperating locking and lifting plates, each formed with valve spindle receiving apertures, said plates being adapted to be assembled face to face and having means on adjacent faces to receive a tool or implement whereby the locking plate may be forced down into the tappet head while the lifting 75 plate may be raised to compress the springs. 80

In testimony whereof the said GEORGE JAMES MORGAN has affixed his signature hereto this 29th day of November 1922.

GEORGE JAMES MORGAN.

In testimony whereof the said RICHARD MILLWARD MORGAN has affixed his signature hereto this 30th day of November 1922.

RICHARD MILLWARD MORGAN.
